MICROPHONE

Robert F. Herrold III, Niles, Mich., assignor to Electro-Voice, Incorporated, Buchanan, Mich., a corporation of Delaware

Filed Feb. 14, 1968, Ser. No. 10,573

Term of patent 14 years

(Cl. D26—14)

Fig.1

Fig. 2

Fig.3

Fig.4

FIGURE 1 is a top plan view of a microphone showing my new design;

FIGURE 2 is a side elevational view of the design shown in FIGURE 1, the reverse side being a mirror image;

FIGURE 3 is an isometric view of the microphone of FIGURES 1 and 2; and

FIGURE 4 is an elevation as seen from the right of FIGURE 3.

The dominant features of my design reside in the portions shown in full lines.

I claim:

The ornamental design for a microphone, as shown and described.
